UNITED STATES PATENT OFFICE.

LOUIS L. JOSEPH, OF CHICAGO, ILLINOIS.

SPINNING-TOP.

1,160,618.

Specification of Letters Patent. Patented Nov. 16, 1915.

Application filed August 26, 1915. Serial No. 47,450.

To all whom it may concern:

Be it known that I, LOUIS L. JOSEPH, a citizen of the United States, residing at Chicago, in the county of Cook and State of Illinois, have invented a new and useful Improvement in Spinning-Tops, of which the following is a specification.

My invention relates to an improvement in the class of tops used as toys and for advertising-display purposes and involving, as essential structural features, a central spindle carrying between its ends a rigid covered disk.

The primary objects of my invention are to provide a simplified construction of top in the class referred to, which shall increase its strength and durability and so accurately balance the parts as to cause comparatively long duration of the spinning of the top.

In the accompanying drawing, Figure 1 is a perspective view of my top; Fig. 2 is an enlarged cross-sectional view of the same, showing the shouldered spindle in elevation, and Fig. 3 is a view like that presented in Fig. 2, but showing the top with the cover-member unprovided with a paper-sheet, on which to display advertising matter, and a shielding transparent covering layer.

The main features of the top are a spindle 4, preferably of wood and tapered at one end to form a spinning-point 5, the spindle being provided between its ends with an enlargement 6 forming shoulders on its opposite faces; a rigid annular disk 7, which I prefer to form of sheet-metal and render slightly concavo-convex by curving it from about its central section, which is formed with a cup-like depression 8, shown as flaring outwardly from a flat base 8^a containing the central opening for the spindle 4 and having a collar 9 to closely hug the spindle, which seats at one shoulder enlargement 6 against the base 8^a; and a cover 10 for the disk 7, preferably formed, like the latter, of sheet-metal and containing a central opening to render it annular for surrounding the spindle and seat the cover against the opposite shoulder of the enlargement, the cover extending over and conforming to the rounded outer surface of the disk, against which it is securely fastened, as by bending its edge-portion circumferentially about that of the disk.

By the provision and disposition of the parts shown and described, the disk and cover are securely clamped together and in

spaced relation about and against the interposed central enlargement 6, the stability of the parts in their assembled relation being materially enhanced by the collar 9 about the spindle; and the assembled parts are so nicely balanced by being thus centralized relatively to the spindle-axis, that the top is readily spun by imparting with the thumb and one or more fingers a twisting motion to the upper section of the spindle, and spins steadily for a comparatively long time in erect position.

Advertising matter may be printed, stamped or otherwise provided for display on the outer surface of the cover 10. Or it may be provided, according to the more amplified construction illustrated in detail in Fig. 2, on a thin sheet of paper 11 conforming to and smoothly covering the disk 7, to which it may be cemented, and bent about the inwardly-turned edge-portion of the disk, which is ornamenteally protected by a shielding transparent layer 12, such as celluloid, secured in place to smoothly cover the paper 11 in the same manner that the latter is fastened to the disk.

I realize that considerable variation is possible in the details of construction thus specifically shown and described, and I do not intend by illustrating specific embodiments of my invention to be limited thereto; my intention being in the following claims to claim protection upon all the novelty there may be in my invention as fully as the state of the art will permit.

What I claim as new and desire to secure by Letters Patent is:

1. A top comprising a central spindle provided between its ends with an enlargement forming opposite shoulders, and a rigid annular disk and an annular cover fastened together on said spindle to embrace between them said enlargement at said shoulders.

2. A top comprising a central spindle provided between its ends with an enlargement forming opposite shoulders, a rigid annular disk and an annular cover fastened together on said spindle to embrace between them said enlargement at said shoulders, a sheet on which advertising matter may be printed and a shielding transparent layer covering said sheet, said sheet and layer extending over and being secured on said cover.

3. A top comprising a central spindle provided between its ends with an enlargement forming opposite shoulders, a rigid annular

disk having a central depression, and an annular cover, said disk and cover being on the spindle and fastened together to embrace said enlargement at said shoulders between the central disk-depression and the central portion of the cover.

4. A top comprising a central spindle provided between its ends with an enlargement forming opposite shoulders, a rigid annular disk having a central depression, and an annular cover, said disk and cover being on the spindle and fastened together to embrace said enlargement at said shoulders between the central disk-depression and the central portion of the cover, a sheet on which advertising matter may be printed and a shielding transparent layer covering said sheet, said sheet and layer extending over and being secured on said cover.

5. A top comprising a central spindle provided between its ends with an enlargement forming opposite shoulders, a rigid annular disk having a cup-shaped central depression provided with a flat base, and an annular cover, said disk and cover being on the spindle and fastened together to embrace said enlargement at said shoulders between the base of said depression and the central portion of the cover.

6. A top comprising a central spindle provided between its ends with an enlargement forming opposite shoulders, a rigid annular disk having a central depression provided with a base and a collar about the opening, and an annular cover, said disk and cover being on the spindle and fastened together to embrace said enlargement at said shoulders between the base of said depression and the central portion of the cover.

7. A top comprising a central spindle provided between its ends with an enlargement forming opposite shoulders, a rigid annular disk having a central depression provided with a collar about the opening, and an annular cover, said disk and cover being on the spindle and fastened together to embrace said enlargement at said shoulders between the base of said depression and the central portion of the cover, a sheet on which advertising matter may be printed and a shielding transparent layer covering said sheet, said sheet and layer extending over and being secured on said cover.

LOUIS L. JOSEPH.
